ELECTRIC CONVERTING APPARATUS

Anthony J. Larrecq, Beach Bluff, Mass., assignor
to General Electric Company, a corporation of
New York

Application September 22, 1939, Serial No. 296,076

15 Claims. (Cl. 175—363)

My invention relates to electric valves and electric converting apparatus, and more particularly to those types of valves in which an arc is periodically ignited and extinguished between a plurality of electrodes and a continuous flow of some fluid medium is maintained between the electrodes.

Electric converting apparatus of the kind referred to have been described in a book by Erwin Marx, entitled "Lichtbogenstromrichter," published in Berlin in 1932, and in United States Letters Patent No. 2,074,930, granted March 23, 1937, upon an application of Erwin Marx. In such apparatus it has been customary to provide a continuous flow of gas, such as air, within the gaps between the electrodes. However, due to the action of oxygen in the air the main electrodes of the prior art devices are subject to considerable deterioration and therefore it has been proposed to use a relatively inert gas instead of air. However, even with the use of such inert gas deterioration of the electrodes is considerable and hence it would be desirable to provide a valve of the gas cooled arc type wherein less burning and deterioration of the electrodes occur. In the arrangements of the prior art it has been necessary to provide an auxiliary electrode which serves as a starting or ignition electrode. In order that this auxiliary electrode may cause the arc discharge to start between the main electrodes considerable auxiliary equipment is necessary. It would be desirable to provide a valve of the gas cooled arc type wherein the auxiliary equipment heretofore required for igniting the arc discharge may be dispensed with along with the difficulties encountered in the operation of such auxiliary equipment. Also in some of the arrangements of the gas cooled arc type of electric valves difficulties have been incurred in extinguishing the arc at the end of the conducting period, i. e., at current zero. In accordance with my invention therefore, I provide an arrangement wherein heretofore necessary auxiliary equipment may be dispensed with, wherein a minimum deterioration of the electrodes occurs, and wherein the extinguishment of the arc at the proper time is much more positive and satisfactory than with apparatus heretofore used.

It is an object of my invention to overcome the disadvantages above noted in connection with valves of the gas cooled arc type and to provide a more efficient and more positive valve for use in connection with electric converting apparatus.

It is another object of my invention to provide

a new and improved electric valve for use in connection with an electric converting apparatus.

Still another object of my invention is to provide an electric valve apparatus including valves of the gas cooled arc type wherein less deterioration of the electrodes occurs and whereby more efficient and more stable operation is obtained.

It is a further object of my invention to provide an electric valve converting apparatus including valves of the gas cooled arc type wherein complicated auxiliary apparatus for initiating the arc discharge at periodic intervals is eliminated and wherein suitable means are provided for extinguishing the arc at the end of the conducting period.

In accordance with the illustrated embodiment of my invention I provide for an electric converting apparatus an electric valve or electric valves of the gas cooled arc type comprising a plurality of stationary segmental electrodes annularly arranged, connected to the respective phases of the alternating current circuit, while an annular collector ring is suitably spaced from said segmental electrodes so as to produce an arc discharge gap therebetween. A segmental conducting member is rotated in synchronism with the alternating current circuit in the arc discharge gap, so reducing this gap that an arc discharge may readily be initiated between one of the segmental electrodes and the collector ring. The rotating conducting member is so dimensioned as to reduce the arc gap only between one segmental electrode at a time and current flowing through the arc discharge is caused to commutate from one segmental electrode to another by the great increase in the arc gap as well as by cooperation of a gas blast which sweeps past the segmental faces causing the arc to move thereacross and to commutate from segment to segment at the proper time. This gas blast is produced by fan means mounted on the rotating member.

The novel features which I believe to be characteristic of my invention are set forth with particularity in the appended claims. My invention itself, however, will best be understood by reference to the following description taken in connection with the accompanying drawing in which Fig. 1 is a cross sectional view of one form of my gas cooled arc type of valve; Fig. 2 discloses the stationary segmental electrodes shown in cross section in Fig. 1; Fig. 3 illustrates the rotating member and fan blades shown in cross section in Fig. 1; Fig. 4 discloses the stationary annular direct current collector ring shown in cross section in Fig. 1, and Fig. 5 is a diagrammatical repre-

sentation of one form of converting apparatus employing my new gas cooled arc type of valve.

Referring to the drawing I have shown in Fig. 1 one form of my gas cooled arc type of valve 10 including a sealed casing 11 mounted on a suitable support 12 which should preferably be constructed of insulating material so that the apparatus may be used for high voltage installations. Mounted within the sealed casing 11 are a plurality of segmental electrodes 13 annularly arranged as best shown in Fig. 2 and lodged in a suitable dielectric or insulating material 14 in such a manner that the segmental faces are flush with the surface of the dielectric 14 so as to permit a smooth path for cooling medium as will be described hereinafter. Although I have shown in Fig. 2 six segmental faces it will be understood by those skilled in the art that there should be as many segmental faces as there are alternating current phases in the converting system with which this electric valve is to be used. The segmental electrodes 13 and dielectric 14 are fixedly supported within the sealed casing 11 by means of an annular support 15. Similarly mounted in the opposite end of sealed casing 11 is a direct current collector ring or electrode 16 of annular shape also suitably lodged in a dielectric or insulating material 17 so that the collector ring 16 is flush with the surfaces of the insulating material thereby to provide a smooth path for the cooling medium as will be described hereinafter. The direct current collector ring 16 is best shown in Fig. 4. This collector ring 16 and insulating material 17 are fixedly supported within casing 11 by means of annular support 18 in such a manner as to provide a relatively large gap or space between segmental electrodes 13 and collector ring 16, and a rotor 19, shown also in Fig. 3, is mounted so as to rotate within the gap formed therebetween. The rotor 19 is integrally mounted or otherwise suitably secured upon a hollow shaft 20 and adapted to rotate with the shaft 20 which is provided with suitable bearings 21 and 22. A synchronous motor 23 drivingly connected to shaft 20 and rotor 19 is preferably mounted directly to casing 11 so as to form an integral unit therewith. Rotor 19 is provided with an enlarged segmental portion 24 of approximately the same circumferential dimensions as segmental electrodes 13 so as to reduce the gap between successive segmental electrodes 13 and collector ring 16 to a minimum. Segmental electrodes 13, enlarged portion 24 of rotor 19 and collector ring 16 are constructed of any suitable conducting material, although in order to reduce deterioration I prefer to use electrodes constructed of a eutectic silver-copper alloy to which has been added a small amount of thorium or barium similar to the electrodes disclosed and broadly claimed in U. S. Letters Patent No. 2,151,567, granted March 21, 1939, upon an application of Hugo J. Seemann, and assigned to the assignee of the present application. Enlarged segmental portion 24 thus produces two relatively short gaps 25 and 26, gap 25 being formed between one of segmental electrodes 13 and enlarged segment 24 of rotor 19 and gap 26 being formed between collector ring 16 and enlarged segment 24 of rotor 19. Gaps 25 and 26 are sufficiently small so that an arc discharge may readily be initiated thereacross and further the arc losses are reduced to a minimum by constructing gaps 25 and 26 as small as possible determined by the necessary minimum running clearance. The remaining portion of rotor 19

has a very narrow cross section so that the gap between the remaining segmental electrodes 13, not adjacent enlarged portion 24 of rotor 19, and collector ring 16 is sufficiently large to prevent an arc discharge from being initiated thereacross and hence also reducing the likelihood of arc backs. By means of synchronous motor 23 rotor 19 is rotated at synchronous speed in the gap between segmental electrodes 13 and collector ring 16 and the enlarged segment 24 is always opposite the particular segmental electrode 13 through which current is to be conducted, by means of arc discharges in gaps 25 and 26, at that particular instant. This current is commutated from one segmental electrode 13 to another as the enlarged portion 24 of rotor 19 continues to rotate. Although I have illustrated segmental electrodes 13, and collector ring 16 as fixedly mounted while member 19 is rotatable, it will be understood by those skilled in the art that all that is necessary is a relative movement between these members and it is immaterial as far as my invention is concerned as to how this relative movement is obtained. A plurality of fan blades 27 are provided on rotor 19 so as to circulate a cooling medium through gaps 25 and 26 as well as through the relatively large gap formed between segmental electrodes 13 and collector ring 16. This cooling medium not only cools the electrodes but also serves to move the arc foot-point diagonally across the segmental faces of electrodes 13. The clearance between fan blades 27 and insulating members 14 and 17 should be reduced to a minimum and it may be preferable to employ labyrinth packing arrangements similar to those used for interstage turbine packing. A plurality of heat transfer surfaces or cooling tubes 28 are provided to cool the fluid medium which leaves the arc discharge gaps 25 and 26. The fluid medium may be continuously recirculated in a closed system by passing through openings 29 and 30 in annular supporting members 15 and 18, respectively. If a closed system is employed the fluid cooling medium will be continually recirculated and cooled by contact with heat transfer members 28. It will, of course, be understood by those skilled in the art, that the pressure of the fluid cooling medium may be suitably chosen as well as the particular type of medium. The particular fluid medium used and the pressure thereof are not critical so far as my invention is concerned and any suitable medium such as air or nitrogen may be used, although I would prefer to use one of the inert gases such as argon in case a closed system is employed. In Fig. 1, however, I have shown an arrangement wherein a cooling fluid circulating system is not completely enclosed in casing 11, but where an additional supply of cooling medium is provided through hollow shaft 20 and openings 31 therein. The pressure of this cooling medium may be controlled by any suitable means (not shown). It will, of course, be understood by those skilled in the art, that if openings 31 in hollow shaft 20 were eliminated then the closed type of system would be provided. Heat transfer members 28 may have any suitable cooling fluid circulated therethrough such as water or air and in certain cases a suitable refrigerant might even be used.

In Fig. 5 I have diagrammatically shown my gas cooled arc type of valve as applied to an electric converting apparatus. It will be understood that my invention is applicable to any electric converting system well known in the art

and it is equally adapted to rectification of alternating current or inversion of direct current. For simplicity of disclosure I have shown in Fig. 5 my invention as employed in connection with a six-phase rectifier circuit wherein electrical energy is transmitted from a three-phase alternating current circuit 33 to direct current circuit 34. A transformer 35 is provided having a delta connected primary winding 36 associated with alternating current circuit 33 and a six-phase star connected secondary winding 37, the respective phases of which are directly connected to one of the segmental electrodes 13. The neutral terminal of star connected secondary winding 37 is connected to the negative terminal of the direct current circuit, while the positive terminal of the direct current circuit is connected to collector ring 16.

The operation of the illustrated embodiment of my invention will best be understood by reference to Fig. 5. Rotor 19 is rotated by means of synchronous motor 23 in synchronism with and in proper phase relationship to alternating current circuit 33 from which synchronous motor 23 is preferably energized. Enlarged section 24 of rotor 19 is so adjusted as to come opposite successive segmental electrodes 13 which have for the particular instant a positive potential applied thereto from alternating current circuit 33 of such a value as to exceed the threshold value of voltage required to initiate an arc discharge across gaps 25 and 26. Each segmental electrode 13 conducts current for substantially sixty electrical degrees after which the succeeding electrode becomes conductive. This happens when the next successive segmental electrode has a sufficiently positive potential applied thereto to exceed the threshold voltage required to initiate an arc discharge across gaps 25 and 26 for at this instant enlarged portion 24 of rotor 19 has reached a position such that its leading edge just overlaps the end of the succeeding electrode. Hence the arc discharge is caused to commutate from one segmental electrode 13 to another partly by the large increase in arc gap which obtains as soon as the trailing edge of enlarged segment 24 has passed the end of the particular segmental electrode which was conducting current and also because of the blast of cooling medium produced by fan blades 27 which causes the arc foot-points to move diagonally across the segmental faces of electrodes 13. Of course, due to the relative movement of the stationary and rotating segmental electrode the arc foot-points naturally tend to move over the face of the same. The large increase in gap is such as to practically eliminate the possibility of arc backs when the high inverse voltage appears across the particular segmental electrode which has just become non-conductive. Furthermore the potential of the segmental electrode 13 which is conducting current varies during the arc discharge so as to produce a minimum potential difference at the instant the arc is being extinguished. The proper phase relationship of rotor 19 and the alternating potentials impressed on segmental electrodes 13 is maintained by suitable adjustment of the synchronous motor field, this adjustment being such that the enlarged segment 24 comes opposite the proper segmental electrode 13 when the potential of the associated alternating current phase exceeds the threshold value of potential required to initiate the arc which passes current from that particular electrode to the direct current collector ring 16. It will be understood

by those skilled in the art that my proposed arrangement is in some respects analogous to the multi-anode, single-cathode electric discharge valves known to the prior art.

While I have described what I at present consider the preferred embodiment of my invention, it will be obvious to those skilled in the art that various changes and modifications may be made without departing from my invention, and I, therefore, aim in the appended claims to cover all such changes and modifications as fall within the true spirit and scope of my invention.

What I claim as new and desire to secure by Letters Patent of the United States, is:

1. In combination a supply circuit, a load circuit, one of said circuits being an alternating current circuit, a transformer and a converting apparatus interconnecting said circuits, said transformer having one winding connected to said alternating current circuit, and a plurality of phase windings inductively associated therewith, said converting apparatus comprising a plurality of angularly spaced electrodes associated with said phase windings, other electrode means mounted in spaced relationship with each of said plurality of electrodes so as to provide a uniform gap therebetween throughout the angular extent of said plurality of electrodes, and means for transmitting electrical energy between successive ones of said plurality of electrodes and said other electrode means comprising a member rotated in said gap in synchronism with said alternating current circuit, said member successively reducing the gap between each of said plurality of electrodes and said other electrode means so as to initiate an arc discharge between said other electrode means and each of said plurality of electrodes in succession, said member having an extent greater than the distance between adjacent ones of said plurality of electrodes so that the arc discharge is readily transferred from one of said plurality of electrodes to the next as said member is rotated.

2. In combination a supply circuit, a load circuit, one of said circuits being an alternating current circuit, a transformer and a converting apparatus interconnecting said circuits, said transformer having one winding connected to said alternating current circuit, and a plurality of phase windings inductively associated therewith, said converting apparatus comprising a plurality of electrodes associated with said phase windings, other electrode means mounted in spaced relationship with each of said plurality of electrodes so as to provide a uniform gap therebetween, and means for transmitting electrical energy between successive ones of said plurality of electrodes and said other electrode means comprising a member rotated in said gap in synchronism with said alternating current circuit, said member successively reducing the gap between each of said plurality of electrodes and said other electrode so as to initiate an arc discharge therebetween, and means for commutating said arc discharge between said plurality of electrodes.

3. In combination an alternating current supply circuit, a direct current load circuit, a transformer and a converting apparatus interconnecting said circuits, said transformer having a primary winding connected to said supply circuit and a polyphase secondary winding, a plurality of stationary electrodes each connected to one of the phases of said secondary winding, a collector ring connected to said direct current cir-

cuit and positioned in spaced relation to said plurality of electrodes and a rotary member including a conducting element mounted between said first mentioned electrodes and said collector ring, and means for driving said rotary member in synchronism with said alternating current supply circuit so that an electrical discharge is produced successively between each of said plurality of stationary electrodes, said conducting element and said collector ring, said conducting element having an extent in the direction of the rotation greater than the distance between adjacent ones of said plurality of electrodes to provide an overlap between said conducting element and adjacent ones of said electrodes as said member is rotated thereby to facilitate the transfer of the arc between said plurality of electrodes.

4. In combination an alternating current supply circuit, a direct current load circuit, a transformer and a converting apparatus interconnecting said circuits, said transformer having a primary winding connected to said supply circuit and a polyphase secondary winding, a plurality of stationary electrodes each connected to one of the phases of said secondary winding, a collector ring connected to said direct current circuit and a rotary member mounted between said first mentioned electrodes and said collector ring, means for driving said rotary member in synchronism with said alternating current supply circuit so that an electrical discharge may be produced successively between said plurality of stationary electrodes and said collector ring, and means for causing a gaseous fluid to cool said arc, driving it across the faces of said electrodes and successively forcing it to transfer from one of said plurality of electrodes to another.

5. An electric valve of the gas cooled arc type for transmitting energy between direct and alternating current circuits comprising a plurality of segmental electrodes and a direct current collector ring so constructed and arranged as to provide a uniform gap therebetween, means for transmitting electrical energy between successive ones of said plurality of electrodes and said collector ring comprising a conducting member rotated in said gap in synchronism with said alternating current circuit, said member successively reducing the gap between each of said plurality of electrodes and said collector ring so as to initiate an arc discharge therebetween and means for causing a gaseous fluid to flow through said gap to aid in the transfer of said arc discharge from one of said plurality of electrodes to another.

6. An electric valve of the gas cooled arc type for transmitting energy between direct and alternating current circuits comprising a plurality of segmental electrodes and a direct current collector ring so constructed and arranged as to provide a uniform gap therebetween, means for transmitting electrical energy between successive ones of said plurality of electrodes and said collector ring comprising a member rotated in said gap in synchronism with said alternating current circuit, said member successively reducing the gap between each of said plurality of electrodes and said collector ring so as to initiate an arc discharge therebetween, and means for commutating said arc discharge between said plurality of electrodes.

7. An electric valve of the gas cooled arc type for transmitting energy between direct and alternating current circuits comprising a plurality of

segmental electrodes mounted within a casing and insulated therefrom, a collector ring mounted within said casing and insulated therefrom, said collector ring being so constructed and arranged with respect to said electrodes as to provide a uniform gap therebetween, means for transmitting electrical energy between successive ones of said segmental electrodes and said collector ring comprising a member rotated with in said gap in synchronism with said alternating current circuit, said member successively reducing the gap between each of said plurality of electrodes and said collector ring so as to initiate an arc discharge therebetween, and means for commutating said arc discharge between said plurality of electrodes by increasing said arc gap when commutation is to take place.

8. An electric valve of the gas cooled arc type for transmitting energy between direct and alternating current circuits comprising a plurality of segmental electrodes mounted within a casing and insulated therefrom, a collector ring mounted within said casing and insulated therefrom, said collector ring being so constructed and arranged with respect to said electrodes as to provide a uniform gap therebetween, means for transmitting electrical energy between successive ones of said segmental electrodes and said collector ring comprising a member rotated with in said gap in synchronism with said alternating current circuit, said member successively reducing the gap between each of said plurality of electrodes and said collector ring so as to initiate an arc discharge therebetween, and means for commutating said arc discharge between said plurality of electrodes by increasing said arc gap when commutation is to take place.

9. An electric valve of the gas cooled arc type for transmitting energy between a direct and an alternating current circuit comprising a plurality of electrodes and a direct current collector ring so constructed and arranged as to provide a uniform gap therebetween, means for transmitting electrical energy between successive ones of said plurality of electrodes and said collector ring comprising a member rotated in said gap in synchronism with the alternating current of said alternating current circuit, said member successively reducing the gap between each of said plurality of electrodes and said collector ring so as to initiate an arc discharge therebetween, and a plurality of fan blades mounted on said member for producing a flow of fluid medium to cool said arc discharge and cause it to commute between said plurality of electrodes.

10. An electric valve of the gas cooled arc type for transmitting energy between direct and alternating current circuits comprising a plurality of segmental electrodes mounted within a casing and insulated therefrom, a collector ring mounted within said casing and insulated therefrom, said collector ring being so constructed and arranged with respect to said electrodes as to provide a uniform gap therebetween, means for transmitting electrical energy between successive ones of said segmental electrodes and said collector ring comprising a member rotated with in said gap in synchronism with said alternating current circuit said member successively reducing the gap between each of said plurality of electrodes and said collector ring so as successively to initiate an arc discharge therebetween,

means for commutating said arc discharge between said plurality of electrodes by increasing said arc gap when commutation is to take place, and a plurality of fan blades mounted on said member for producing a flow of gaseous medium within said casing for cooling said arc discharge and aiding the commutation from one electrode to another.

11. An electric valve of the gas cooled arc type for transmitting energy between a direct and an alternating current circuit comprising a plurality of electrodes and a direct current collector so constructed and arranged as to provide a uniform gap between said electrodes and said collector, means for transmitting electrical energy between successive ones of said plurality of electrodes and said collector comprising a member rotated in said gap in synchronism with the alternating current of said alternating current circuit, said member successively reducing the gap between each of said plurality of electrodes and said collector so as to initiate an electrical discharge therebetween, means for producing a flow of fluid medium to cool said arc discharge and cause it to commutate between said plurality of electrodes, and heat transfer means in the path of said fluid medium to cool said fluid medium after it has been heated by said arc discharge.

12. An electric valve of the gas cooled arc type for transmitting energy between direct and alternating current circuits comprising a casing, a plurality of electrodes and a direct current collector insulatingly mounted therein, said collector being so arranged in said casing with respect to said plurality of electrodes as to provide a uniform gap therebetween, means for transmitting electrical energy between successive ones of said electrodes and said collector comprising a member arranged to be rotated within said gap, a synchronous motor mounted on said casing drivingly connected to said member and rotating it within said gap in synchronism with said alternating current circuit, said member successively reducing the gap between each of said plurality of electrodes and said collector so as to successively initiate an arc discharge therebetween, and means for commutating said arc discharge between said plurality of electrodes by increasing said electric gap when commutation is to take place.

13. In combination, a supply circuit, a load circuit, one of said circuits being an alternating current circuit provided with a plurality of phase terminals, a converting apparatus interconnecting said phase terminals and said other circuit, said converting apparatus comprising a plurality of electrodes mounted in electrically insulated and closely spaced circumferential relation associated with said phase terminals, other electrode means mounted in spaced relationship with each of said plurality of electrodes so as to provide a uniform gap therebetween, and means for transmitting electrical energy between successive

ones of said plurality of electrodes and said other electrode means comprising a member rotated in said gap in synchronism with said alternating current circuit, said member successively reducing the gap between each of said plurality of electrodes and said other electrode means so as to initiate an arc discharge therebetween, said member being dimensioned to overlap portions of successive ones of said plurality of electrodes as the member is rotated to thereby facilitate the commutation of current from one of said pluralities of electrodes to the next.

14. An electric valve of the gas cooled arc type for transmitting energy between a load circuit and a supply circuit, one of said circuits being an alternating current circuit, comprising a plurality of electrodes and a direct current collector ring so constructed and arranged as to provide a uniform gap therebetween, and means for transmitting electrical energy between successive ones of said plurality of electrodes and said collector ring comprising a conducting member mounted so as to be relatively rotatable with respect to said plurality of electrodes, said relative rotation being in synchronism with said alternating current circuit thereby successively reducing the gap between each of said plurality of electrodes and said collector ring to initiate an arc discharge therebetween and means for directing a flow of gaseous fluid across said gap for aiding the commutation of said arc discharge from one of said pluralities of electrodes to another as said conducting member is rotated.

15. In combination, a supply circuit, a load circuit, one of said circuits being an alternating current circuit, a transformer and a converting apparatus interconnecting said circuits, said transformer having one winding connected to said alternating current circuit and a plurality of phase windings inductively associated therewith, said converting apparatus comprising a plurality of electrodes associated with said phase windings and mounted in electrically insulated and closely spaced circumferential relation, other electrode means mounted in spaced relationship with each of said plurality of electrodes so as to provide a uniform gap therebetween, and means for transmitting electrical energy between successive ones of said plurality of electrodes and said other electrode means comprising a conducting member mounted in said gap so as to be relatively rotatable with respect to said plurality of electrodes, said relative rotation being in synchronism with said alternating current circuit thereby successively reducing the gap between each of said plurality of electrodes and said other electrode means so as to initiate an arc discharge therebetween, said member having sufficient extent in the direction of rotation thereof to overlap successive ones of said electrodes to thereby facilitate the commutation of said arc discharge between successive electrodes.

ANTHONY J. LARRECQ.
